UNITED STATES PATENT OFFICE.

ROGER A. SELBY, OF PORTSMOUTH, OHIO, ASSIGNOR TO THE SELBY SHOE COMPANY, OF PORTSMOUTH, OHIO, A CORPORATION OF OHIO.

DESIGN FOR A SHOE.

Application filed March 9, 1929. Serial No. 30,401. Term of patent 3½ years.

To all whom it may concern:

Be it known that I, ROGER A. SELBY, a citizen of the United States, residing at Portsmouth, in the county of Scioto and State of Ohio, have invented a new, original, and ornamental Design for Shoes, of which the following is a specification, reference being had to the accompanying drawing, forming part thereof.

Fig. 1 is an inner side view of a shoe showing my new design; and Fig. 2 is an outer side view of the same.

I claim:

The ornamental design for a shoe, as shown.

ROGER A. SELBY.
